CLAIM

The ornamental design for an escutcheon for wall mountable accessories, as shown and described.

DESCRIPTION

In a preferred embodiment, the nature of this product is as a wall mountable escutcheon primarily useful for supporting an accessory in the form of a towel bar, toilet paper holder, robe hook, or towel ring.

FIG. 1 is a top, left, front perspective view of an escutcheon for wall mountable accessories embodying my new design; FIG. 2 is a front elevational view thereof;

FIG. 3 is a top plan view thereof, the bottom plan view thereof being identical to the top plan view shown;

FIG. 4 is a left side elevational view thereof, the right side elevational view thereof being identical to the left side shown;

FIG. 5 is a rear elevational view thereof;

FIG. 6 is a top, left, front perspective view thereof showing the broken line representation of a single towel bar as a first mounting environment;

FIG. 7 is a top, left, front perspective view thereof showing the broken line representation of a double towel bar as a second mounting environment;

FIG. 8 is a top, left, front perspective view thereof showing the broken line representation of a toilet paper holder as a third mounting environment;

FIG. 9 is a top, left, front perspective view thereof showing the broken line representation of a robe hook as a fourth mounting environment; and,

FIG. 10 is a top, left, front perspective view thereof showing the broken line representation of a towel ring as a fifth mounting environment.

The broken line representations of mounting holes in FIGS. 1, 2, and 5, of rear structure in FIG. 5, and of accessories in FIGS. 6-10, are for the purpose of illustration only, and form no part of the claimed design.
